UNITED STATES PATENT OFFICE.

MIRZA H. BENSON, OF DES MOINES, IOWA, ASSIGNOR OF ONE-HALF TO E. CHANNING EVANS, OF DES MOINES, IOWA.

LOCK.

1,223,928.

Specification of Letters Patent. Patented Apr. 24, 1917.

Application filed July 18, 1914. Serial No. 350,811.

To all whom it may concern:

Be it known that I, MIRZA H. BENSON, a citizen of the United States, and resident of Des Moines, in the county of Polk and State of Iowa, have invented a certain new and useful Lock, of which the following is a specification.

The object of my invention is to provide a lock of comparatively simple and durable construction, of the ordinary padlock type, and having a casing with two cylindrical openings extending through it, provided also with locking bolts adapted to extend into said opening, which lock is used in combination with a shackle with arms adapted to extend into said openings, and provided with notches to be engaged by said locking bolts.

My invention consists in certain details, in the construction, combination and arrangement of the various parts of the device, whereby the objects contemplated are attained, as hereinafter more fully set forth, pointed out in my claim and illustrated in the accompanying drawings, in which:

Figure 1 shows a side elevation of a lock, embodying my invention.

Fig. 2 shows a similar view of the same, portions of the lock casing being cut away to show the locking bolts and the openings extending through the casing, and the manner in which the shackle is locked in position.

In the accompanying drawing, I have used the reference character A to indicate generally the ordinary padlock, which has the casing 10 through which extend two vertical openings 11. Ordinary locking mechanism is provided, which locking mechanism includes locking bolts 12, adapted in one position of their movement to extend into the respective openings 11. Any spring actuated bolts may be used and the spring mechanism has therefore not been shown in detail.

It is desirable in many instances to employ a padlock having a shackle which can be placed over a staple and a catch device or over two levers or the like. A definite example of the use of a device such as herein described will be hereinafter mentioned.

For use with the padlock member A I provide a shackle 13, having the parallel arms 14, adapted to be extended through the openings 11, as shown in the drawing. The ad-

jacent faces of the parallel arms 14 are provided with pluralities of notches 15, as shown. In locks of this type, the bolt 12 on one side may be placed near the upper part of the lock and the bolt 12 on the other side may be placed at the lower part of the lock, as shown in Fig. 2. Where the bolts are located as just described, the notches 15 of each of the arms 14 are properly spaced apart so that when the arms 14 are inserted into the openings 11 the bolt 12 near the lower part of the lock may be received in one of the notches in one of the arms 14 and the bolt 12 near the upper part of the lock may, at the same time, be received in one of the notches in the other arm 14, as clearly shown in Fig. 2.

Where a lock of this type is used, as for instance to lock together the throttle and spark controlling levers on an automobile steering wheel, and to secure them to one of the spokes of the wheel, it is desirable to have a shackle 13 of such size as to make it possible to lock the levers to the spokes of automobiles of different makes and sizes. It is therefore desirable that the space between the lock member A and the closed end of the member 13 be adjustable so that the lock may be used for a variety of purposes. Such adjustability is accomplished by the construction hereinbefore set forth. The members 14 may be pushed through the openings 11 as far as desired so that the opening between the member A and the closed end of the shackle can be made smaller or larger according to the circumstances of the use to which the lock is put. In the ordinary lock of this kind, the openings 11 are entirely closed at one end and the shackle can be locked in only one position.

It will be understood that some changes may be made in the details of the construction of my completed lock without departing from its essential features, and it is my intent to cover by this application any such changes which may be included within the scope of the following claim.

I claim as my invention:

A lock of the class described comprising a casing having locking bolts arranged there-in in staggered relation with each other, a yoke having opposite arms slidably extended through said casing, said arms being pro-

vided in their adjacent faces with pluralities of notches to receive said locking bolts, said locking bolts having beveled ends adapted to permit said arms to slide freely in said casing in one direction, the parts of said device being so arranged that the free ends of the locking bolts enter the notches

in the respective arms at points at different distances from the closed end of the yoke.

Des Moines, Iowa, July 6, 1914.

MIRZA H. BENSON.
